UNITED STATES PATENT OFFICE

160,381

COMBINATION SINK AND WASHING
MACHINE

Andrew H. Gerhardt, Skokie, Ill., assignor to
Thor Corporation, Chicago, Ill., a corporation
of Illinois

Application August 12, 1948, Serial No. 148,070

Term of patent 14 years

(Cl. D33—19)

To all whom it may concern:

Be it known that I, Andrew H. Gerhardt, a citizen of the United States, residing at Skokie, in the county of Cook and State of Illinois, have invented a new, original, and ornamental Design for a Combination Sink and Washing Machine, of which the following is a specification, reference being had to the accompanying drawing, forming a part thereof.

In the drawing:

Figure 1 is a perspective view showing the front, top and right-hand side of a combination sink and washing machine, embodying my new design.

Fig. 2 is an enlarged fragmentary sectional view taken along the lines 2—2 in Fig. 1.

Fig. 3 is an enlarged front view of one of the handle elements taken separately and shown broken for convenience of illustration.

The left-hand end of the combination sink and washing machine is similar to the end shown, and the back is essentially plain.

I claim:

The ornamental design for a combination sink and washing machine, substantially as shown and described.

ANDREW H. GERHARDT.
